UNITED STATES PATENT OFFICE.

JAMES W. PATERSON, OF CHICAGO, ILLINOIS.

SHADE-FIXTURE.

SPECIFICATION forming part of Letters Patent No. 659,815, dated October 9, 1900.

Application filed May 11, 1900. Serial No. 16,249. (No model.)

To all whom it may concern:

Be it known that I, JAMES W. PATERSON, a citizen of the United States, residing at Chicago, in the county of Cook and State of Illinois, have invented a new and useful Improvement in Shade-Fixtures, of which the following is a specification.

This invention relates to an improvement in shade-fixtures of that class adapted to be secured at the lower margin of a curtain-shade or the like and having at the opposite ends thereof parts adapted to engage the jamb of the window in which said shade is secured. Heretofore devices have been provided for this purpose having at each end of the curtain-rod a head provided with laterally-extending arms held yieldingly in a groove of the window-jamb and acting to cause the rod to assume a horizontal position when one end thereof is drawn down more than the other. This has been open to the objection that unequal strain on the two sides of the shade tends to injure or tear the same, thus greatly reducing the life of the curtain and causing unnecessary expense.

The object of my invention is to provide a device of the class described constructed in such manner that the same at all times holds the lower margin of the shade in a horizontal position.

The invention consists in the matters hereinafter described, and more fully pointed out and defined in the appended claims.

In the drawings, Figure 1 is a front elevation of a window and shade provided with a device embodying my invention. Fig. 2 is a longitudinal vertical section of one end of the shade-fixture. Fig. 3 is an end elevation of the same.

As shown in the drawings, in which my invention is shown as applied to a car-window, A indicates a curtain-shade. A' indicates a tubular rod secured to the lower horizontal margin of said shade in any desired manner and having the ends thereof projecting, as shown, slightly beyond the side margins of the same.

B indicates the window-sash. C indicates the frame therefor, the jambs thereof having in the vertical sides thereof adjacent to said sash vertical grooves, as shown in Fig. 1, adapted to receive therein the heads A³ A³,

rigidly secured at opposite ends of said tubular rod. Said vertical grooves may be provided in the jamb itself or vertical stops c may be secured on the inner face of each jamb, providing between the same a groove adapted to receive said heads. A² A² indicate milled nuts, each provided with an axial aperture and adapted to engage, respectively, the opposite ends of said tubular rod and provide a connection between the same and said heads A³ A³. Said heads, as shown, are each provided on each side thereof with oppositely-extending arms a² a², directed at right angles with the tubular rod A'. Said arms are provided at their outer ends with rollers a³, adapted to track on said jambs within said grooves and designed to permit vertical movement of said device as a whole.

D D indicate longitudinally-movable rods or plungers yieldingly secured, respectively, each in one end of said tubular rod A' and having the outer ends thereof each provided with a friction-foot D', adapted to be pressed yieldingly against the jamb of the window in said groove and acting to resist vertical movement of said rod.

Referring now more particularly to features of construction, the said curtain or shade A will usually be provided at its top with a spring-roller of any desired construction or other means permitting vertical movement of the curtain in said frame. The said rod A' is secured to the lower horizontal margin of said shade in any desired manner and may be either tubular throughout its entire extent or may be provided with tubular ends, said ends, as shown, being provided with internal screw-threads and projecting slightly beyond the lateral margin of the curtain. The milled nut A² has at one end thereof screw-threads complementary to the screw-threads in the end of the rod A', and at its other end is of reduced diameter and, as shown, is provided with a peripheral groove. The milled portion of said nut A² is located centrally thereof and, as shown, is of the same diameter as the rod A' and forms when screwed into the end thereof essentially a continuation of the same. The heads A³ A³ may be constructed of casting, of brass or other suitable metal, or may be formed of sheet or stamped metal, as preferred. The

same are secured upon the ends of the rod A' by means of the said milled nuts, the reduced grooved ends of which are secured each in a socket located centrally of said head by means of a set-screw engaging the walls of said head and having its inner end within said groove of said nut. Said heads on the outer side thereof or that adjacent to the jamb are straight, and the arms a² a² thereof are in alinement and adapted to have sliding movement within said groove. The rollers a³ a³, secured at the outer ends of said arms, project beyond the vertical face thereof into position to engage the jamb, and thereby provide an antifriction device adapted to permit like movement at each end of said rod independent of the point of application of force.

Within each tubular end of the rod A' is secured the tail-block d. The same is provided with an axial aperture and may be secured in place by any desired means, that herein shown being a set-screw d', acting to force said tail-block into engagement with the inner surface of the tubular rod A'. Said nuts A² and heads A³ are also provided with axial apertures, and a socket or recess is formed in the vertical face of each head, adapted to secure within the same the friction-foot D'. Said friction-feet, as shown, consist each of a block or clip of metal adapted to lie within said recess in a head A³, longitudinally thereof, and are each provided on their outer side with a pad of resilient material, such as leather or the like. The same are provided centrally on the inner side with a socket adapted to receive and afford attachment for the outer end of the plunger D. Said plungers are located one in each end of said rod A', with the inner end thereof lying in the aperture of said tail-block and with the outer end of the same extending outwardly through the apertures in said nut and head and rigidly secured to the friction-foot, as before described. The said plunger near its middle part is provided with a stop d³, rigidly secured thereto, and a pushing-spring, herein shown as a spiral spring, surrounds said rod. One end thereof engages the said stop and the other of which engages the tail-block d, thereby acting to hold the outer end of said rod, with the friction-foot thereon, in its extended position. For the purpose of providing greater amplitude of movement for the said rod the milled nut A² may be provided at its inner end with a socket or recess adapted to receive the stop d³ and the end of the spring d⁴; but obviously the same is not essential to the successful operation of this invention.

Obviously if a rod having a solid central part and provided with tubular ends be used the tail-block d may be omitted.

The operation of my device is as follows: 65 The tubular rod A' being secured on the lower margin of the curtain or shade, as indicated in Fig. 1, and the parts assembled, as indi-

cated in Fig. 2, the device is adjusted to the window-frame by turning the milled nut A² inwardly or outwardly. Inasmuch as the device is symmetrical, or, in other words, is provided with like ends, a large adjusting-space is not necessary. One end of the device having been inserted in the groove on the front face of the window-jamb, the length of the device may be modified by means of rotation of said milled nuts at each end thereof to permit the insertion of the opposite end in the corresponding groove. The rod may be lengthened sufficiently by the reverse rotation of one or both of said nuts to bring the wheels or rollers at each end of the device into bearing contact against the jamb. Obviously when all four of said rollers are in bearing contact the curtain-rod must necessarily be 85 in a horizontal position. The friction-foot D', forced outwardly by the action of its springs into contact with the respective jambs adjacent thereto, acts to hold the shade from upward or downward movement. Obviously 90 the said springs may be adjusted to any desired degree of tension, thereby permitting said friction-feet to be held lightly against said jambs or to be pressed against the same with considerable force, as may be desired. 95 It is also obvious from the construction described that the said heads, while adjustable longitudinally of the rod, are when once adjusted held rigidly with respect thereto and that in consequence downward movement at 100 one end of said curtain-rod will of necessity produce a like vertical movement at the other end thereof, or, in other words, the rigidity of the connection of the head and the rod and the antifriction-bearings at the extremity of 105 each arm of each head operates to produce corresponding movement in each end.

I claim as my invention—

1. In a shade-fixture a rod adapted to be secured to the lower margin of a shade and provided at each end with a head having arms oppositely extended at right angles with said rod, means for adjusting said heads longitudinally of said rod and rigidly securing the same relatively to said rod in their adjusted 110 positions, and antifriction devices at the extremity of each arm adapted at all times to engage the window-jamb whereby said rod is at all times held in a horizontal position.

2. A holding mechanism for spring-actuated shades or the like, comprising a rod secured to the lower margin of a shade and provided at each end with a head, means for adjusting said heads longitudinally of the rod and rigidly securing the same relatively to 115 said rod, an arm on each head forming right angles with said rod, a roller at the extremity of each arm adapted at all times to bear against a window-jamb or the like and a friction device movable with respect to said heads 120 said rod and adapted to yieldingly engage said window-jamb.

3. A holding device for spring-actuated shades comprising a rod having tubular ends

and adapted to be secured to the lower margin of a shade or the like, a head secured on each end of said rod and adjustable longitudinally thereon, means for rigidly securing 5 said head in its adjusted position, arms on each head extending at right angles with said rod and oppositely from each other, an anti-friction device at the extremity of each arm adapted to engage at all times a window-jamb 10 or the like and a spring-pressed friction-pad longitudinally movable with respect to said rod and adapted to engage the jamb intermediate of the extremities of said arm.

4. In a shade-holding mechanism, a tubular 15 rod mounted on the lower margin of a shade or the like, and provided at its ends with screw-threads, a milled nut provided at one end with screw-threads complementary to those of said rod and at its opposite end provided 20 with a peripheral groove, a head provided with a central socket adapted to rotatively engage the grooved end of said milled nut and oppositely-directed arms on each head extending at right angles with said rod, antifriction 25 devices at the extremity of each arm, a plunger longitudinally movable with respect to said rod and provided at its outer end with a resilient pad adapted to engage the jamb and a spring engaging said plunger acting normally 30 to hold the padded end thereof pressed against the jamb.

5. In a device of the class described a curtain-rod provided with tubular ends having at its extremities interior screw-threads, a 35 milled nut provided at one end thereof with screw-threads complementary to those on said rod, a head having rotative engagement with said nut and longitudinally adjustable with respect to the same, arms on said head extending oppositely at right angles with said rod 40 and provided at their outer ends with rollers adapted to engage the jamb of a window or the like, a plunger in each end of said rod the outer ends whereof extend through said nuts 45 and heads, a friction-pad at the outer end of each plunger and springs in the tubular ends of said rod engaging said plungers whereby the same are held normally in their extended positions.

6. In a device of the class described a tubular rod adapted to be secured at the lower horizontal margin of a curtain or the like, means for maintaining the same at all times in a horizontal position comprising heads longitudinally adjustable with respect to said 50 rod and rigid with respect to the same in their adjusted positions, oppositely-extending arms on each head forming approximately right angles with said rod and adapted to engage the vertical faces of the jambs in grooves provided 55 therefor and a rotatable part forming the connection between said heads and said rod and adapted to provide for the longitudinal adjustment of the same by the rotation thereof.

7. In a holding device for spring-actuated 60 shades a tubular rod adapted to be secured at the lower horizontal margin of a shade, a head secured at each end of said rod and provided with upwardly and downwardly extending arms forming right angles with said 65 rod and adapted to engage the window-jams in grooves provided therefor, antifriction devices at the extremity of each arm adapted to bear against said jamb, a plunger having movement longitudinally of said rod and secured within the same the outer end thereof passing outwardly through said head, an elongated friction-pad parallel with said arms and adapted to engage the jamb in the plane thereof, a pushing-spring engaging with one of its 70 ends said rod and with its other end said plunger whereby the same is normally held in its extended position, means for longitudinally adjusting said heads with respect to said rod comprising a milled nut having screw-threaded 75 engagement with said rod and rotative engagement with said head, whereby rotation in one direction acts to draw said head inwardly toward said rod and rotation in the opposite direction moves the same outwardly 80 therefrom.

In testimony whereof I have signed my name, in the presence of two witnesses, this 27th day of April, 1900.

JAMES W. PATERSON.
